HARRY W. BRADNER, OF TACOMA, WASHINGTON, ASSIGNOR, BY DIRECT AND MESNE ASSIGNMENTS, TO THE GENERAL PATENTS COMPANY, INC., OF NEW YORK, N. Y., A CORPORATION OF NEW YORK.

EXTENSION-TABLE.

1,080,043.

Specification of Letters Patent.

Patented Dec. 2, 1913.

Application filed May 20, 1912. Serial No. 693,447.

To all whom it may concern:

Be it known that I, HARRY W. BRADNER, a citizen of the United States, residing at Tacoma, in the county of Pierce and State of Washington, have invented a certain new and useful Improvement in Extension-Tables, of which the following is a specification.

The invention relates to extension tables in the class of household furniture and more particularly to that type supported at the center by a pedestal leg, and the objects of the invention are to provide mechanism by which the halves of the table-top are so connected as to move oppositely to equal distances in the opening and closing movements, thus maintaining balance; and permitting the table to be opened or closed by one person alone at one end, the other end moving automatically, and to provide means for insuring the easy movement of the slides and lessening or entirely avoiding the liability of the moving parts to bind.

The invention consists in certain novel features and details of construction by which the above objects are attained, to be hereinafter described.

The accompanying drawings form a part of this specification and show an approved form of the invention.

Figure 1 is a plan view of the table in the opened condition. Fig. 2 is a plan view of the slides and connected parts on a larger scale, the table-top being indicated by dotted lines. Fig. 3 is a corresponding vertical section taken transversely of the slides on the dividing line of the table-top, and partly in elevation. Fig. 4 is a central vertical section of a portion, taken at a right angle to the view in Fig. 3, and partly in elevation. The remaining figures are on a still larger scale and show the construction of the slides. Fig. 5 is a transverse vertical section through the slides. Fig. 6 is a corresponding horizontal section, partly in plan view, the plane of section being indicated by the line 6-6 in Fig. 5. Fig. 7 is an elevation of the working face of one of the slides.

Similar letters of reference indicate the same parts in all the figures.

A is the upper part of a pedestal having a cap-piece A¹ carrying the operating mecha-

nism and supporting the two halves A² A² of the table-top. Mounted upon and fixed to the cap-piece near each end is a fixed guide C forming the central member of a set of slides to be further described, and at the center, lying parallel with the slides, is fixed a bar D extending diametrically of the table and as nearly as may be to the outer margin of each half of the table-top, when in the closed condition; it carries on its upper face at each end a pulley E partially encircled by a cord or belt F which is in effect continuous but is divided at two points for attachment to the ends of arms G, G located between the center-bar D and the sets of slides, each fixed to one portion of the table-top and extending some distance beyond the dividing line between the two halves thereof. By this arrangement of cords and pulleys a movement of one portion of the table-top is communicated to the other, so that in opening or closing the table-top the movement of one half in either direction automatically causes a corresponding movement of the other half to the same extent and in the opposite direction, thus insuring the desired balance and permitting the opening and closing movements to be easily effected by one person pulling or thrusting on one of the halves alone.

In order to utilize effectually the support offered to each half by the overhanging ends of the strong central bar D, the vertical pins E¹ E¹ serving as centers for the pulleys E E are each provided with a forked head or yoke E² in which is mounted a small grooved roller H matching to a cylindrical track H¹ on the under face of each portion of the table-top, and which may be a cylindrical wire lying upon or partially embedded in such face and secured by driving its upturned ends H² H² into the material of the table.

The tracks and rollers permit the table-top to be supported by the central bar D, at points as distant as practicable from the center of the table, and allows the halves to be moved antifrictionally relatively to such bar. The sets of slides are also constructed to move with a minimum of friction while maintaining reliable engagement each with its neighbor. Each set is a counterpart of the other and comprises the relatively fixed

central member C above referred to, and a 5
slidable member J or K on each of the side
faces thereof, one attached to one portion
of the table-top and the other to the opposite
portion, to move therewith.

The adjacent faces of the several slides
J, C, K, are grooved near the upper and
lower edges to produce channels as at *j c k*
and form the longitudinally extending cen- 10
tral ribs J¹ C¹ C² K¹ between the channels.
On each rib is a strip or flat bar of metal B
wider than the rib and extending partially
over the adjacent channels, and having its
edges rounded. These strips B B lie face
15 to face in pairs and at one end each is
forked as at B¹ and the branches folded to
form housings B² receiving pins B³ serving
as shafts for small rollers B⁴ mounted in
the housings and grooved on the periphery
20 to match closely to and engage the rounded
edges of the adjacent strip.

The fork B¹ of each strip is at the oppo- 25
site end from its neighbor, and the over-
hanging portions of the housings and their
rollers are received in the channels. The
strips of each pair are thus joined together
30 with liberty to move longitudinally rela-
tively to each other with their attached
slides, the rollers serving as the means of en-
gagement and in reducing the friction.

To limit the outward movement of the
strips and slides and the separation of the
two halves of the table-top, a projection or
spur B⁵ is produced on the upper edge of
35 each strip at the proper location, arranged
to strike or be struck by the upper roller
B⁴ of the adjacent strip and arrest the out-
ward movement; the inward movement is
arrested by the contact of the two halves of
40 the table-top, as will be understood.

Thus constructed and arranged, the sev- 45
eral parts of the table are reliably joined
while the required movements are permitted
with but little friction, and slight changes
of the materials employed, due to hygro-
metric conditions, do not interfere with the
working of the mechanism.

Modifications may be made in the forms
and proportions of the parts without de-
50 parting from the invention, and parts may
be used without the whole.

The cord F may be a chain or other flexi-

ble connection, and the track H¹ may be con-
structed and attached in a different manner
than that shown and described.

No claim is made herein to the outer slide
structure, as the same forms the subject-
matter of an application filed February 8,
1913, as a division thereof, Serial No.
747,026.

60

I claim:—

1. An extension table having a bar ex-
tending transversely of the table-joint and a
horizontally arranged pulley at each end of
said bar, cords attached to the halves of the
table-top and extending partially around
55 said pulleys to induce equal and opposite
movements of such halves, a track on the
under face of each of said halves, and ver-
tically arranged rollers mounted on said bar
70 in engagement with said tracks.

2. An extension table having a bar ex-
tending transversely of the table-joint and
a horizontally arranged pulley at each end
75 of said bar, cords attached to the halves of
the table-top and extending partially around
said pulleys to induce equal and opposite
movements of such halves, a track on the
under face of each of said halves, pins serving
80 as centers for said pulleys, a yoke on the
upper end of each of said pins, and a verti-
cally arranged roller supported in said yoke,
said rollers adapted to engage said tracks.

3. An extension table having a bar ex-
tending transversely of the table-joint and
85 a horizontally arranged pulley at each end
of said bar, cords attached to the halves of
the table-top and extending partially around
said pulleys to induce equal and opposite
movements of such halves, a cylindrical
90 track on the under face of each of said
halves, pins serving as centers for said pul-
leys, a yoke on the upper end of each of said
pins, and a vertically arranged grooved
roller supported in said yoke, said rollers
95 adapted to engage said tracks.

In testimony that I claim the invention
above set forth I affix my signature, in pres-
ence of two witnesses.

HARRY W. BRADNER.
